UNITED STATES PATENT OFFICE.

CLARENCE M. DEASON, OF CARNEGIE, OKLAHOMA.

COMBINATION COMB AND BRUSH.

1,280,180.

Specification of Letters Patent.

Patented Oct. 1, 1918.

Application filed March 15, 1917, Serial No. 154,981. Renewed August 19, 1918. Serial No. 250,620.

To all whom it may concern:

Be it known that I, CLARENCE M. DEASON, a citizen of the United States, residing at Carnegie, in the county of Caddo, State of Oklahoma, have invented certain new and useful Improvements in Combination Combs and Brushes; and I do hereby declare the following to be a full, clear, and exact description of the invention, such as will enable others skilled in the art to which it appertains to make and use the same.

This invention relates to combination combs and brushes, and has particular reference to that type of combination articles in which the comb is embodied in the brush body for projection or retraction, as the needs of the user require.

The object of the invention is to simplify the construction of brushes of this type, and to provide one which may be readily dismantled for cleaning or inspection. To this end, I have constructed the brush body with a removable back which coöperates with the body to form a dome or cavity into which the comb member is retracted, so as to be entirely clear of the bristles and also to be accessible for cleansing. It should be mentioned at this point that the removable back also forms a hand grip, which may be grasped, when the comb is in its operative position, to more effectively direct the latter through the hair.

With the above objects in view, and such others as may hereinafter appear as relating to the details of structure, my invention will now be more fully set forth and described, reference being had to the accompanying drawings.

In the drawings,

Figure 1 is a back view of the brush, Fig. 2 is a section on line 2—2 of Fig. 1, Fig. 3 is a back view with the back covering removed, and

Fig. 4 is a section on line 4—4 of Fig. 1. Referring more particularly to the drawings, 1 represents the brush body, which is elongated at one end to provide the usual handle 2, and carries also the bristle body 3 in any of the well known or accepted manners. Formed longitudinally of the body 1 is a slot 4, which continues into the handle portion 2 for a suitable distance, preferably terminating in the narrow portion of handle, just in front of the hand grip. Mounted in the slot 4 is the comb 5, which is a structure modified somewhat from the usual

comb formation, in that the back thereof is widened throughout the length of the comb, and at a plurality of points, probably two, web portions 6 are continued downwardly from the back into the teeth. Formed in parallel relation and diagonally to the back, are the cam slots 7, which extend from the upper portion of the back downwardly into the web portions 6, so that a maximum elongation of the slots may be obtained.

The cam slots 7 are engaged by a pair of transverse pins 8 which traverse the slot 4, the pins 8 holding the comb in position, and co-acting with the slots 7 as the comb body 70 is urged longitudinally of the brush body, to withdraw or project the comb teeth away from or through the bristle body. It will be noted that the direction and inclination of the slots 7 is such that the teeth of the 75 comb will be practically fully retracted from the bristles when the comb is pulled rearwardly with relation to the brush body, that is toward the handle 2, and that the teeth will be projected beyond the lower or free 80 ends of the bristles when the comb is pushed forwardly.

Connected to the rear end of the comb body is a pair of links 9, which lie on opposite sides of the comb and are connected 85 by means of the rotary pin 10 having its journal in the comb back. The opposite ends of the links 9 are pivotally connected to the ears 11 which are extended downwardly from a plate 12, the plate 12 being mounted 90 upon a bridge-piece 13 whose feet are provided with longitudinal bearings 14 which are vertically elongated to a slight degree. The bearings 14 ride upon a rod 15 which is mounted to extend midway along the forward end of the slot 4, its forward end being fixed in the end of the slot and its rear end projecting freely therein. A head 16, which may be of any ornamental character, serves as a grip to slide the bridge-piece along the 100 rod 15. The rod 15 is provided on its under side with a series of teeth 15', and the lower ends of bearing slots 14 are edged to engage said teeth. To hold the comb body in its position of adjustment, a leaf spring 17 is 105 secured into the forward end of the slot 4, and bears on the lower ends of the feet of the bridge-piece 13, so that as the latter is actuated from the head 16, to release and adjust the comb, the spring 17 tends to return the bearings 14 into engagement with the teeth 15'.

The longitudinal edges of the brush body, are grooved throughout their lengths to form channels 18 within which are slid the inturned flanges 19 of a cover plate or back 20. The back 20 is made of any suitable material, such as metal, celluloid or a molded plastic, and arches over the body 1 to provide a cavity 21 within which the comb may enter when it is in its retracted position, this cavity permitting the teeth to be fully withdrawn from the region of the lower or active portions of the bristles. The cover plate, when slid into position, fully incloses the body 1 and the comb mechanism, except the head 16 and that portion of slot 4 which it is necessary to leave uncovered for the operation of the latter. A set screw 22 is entered through the cover 20 and into the body 1 in order to hold the cover in place.

The manner of use of my improved device will be apparent from the foregoing description, but it should be particularly noted that the comb and brush are so related that each may be used without noticeable effect of the other on the hair. The back 20 is formed to permit a ready grasp of the body of the brush, so that when used with the comb projected, it may be more suitably and conveniently directed. The mechanism is simple, and can be embodied in any of the conventional forms of brushes, without creating a bulky or unsightly article.

35 What I claim as my invention is:—

1. A combined brush and comb, consisting of a body having a longitudinal slot formed therein, a comb mounted in said slot for projection and retraction beyond and 40 into the bristle body of the brush, and means for actuating the comb, and means to hold the comb in position at various degrees of projection.

2. A combined brush and comb, consisting of a body having a longitudinal slot formed therein, a comb mounted in said slot and having a plurality of diagonal cam

slots formed in its back means engaging said cam slots to throw the comb below the bristles of the brush when the former is moved longitudinally of the slot in the body, and means to move the comb, and means to hold the comb at various lines of projection. 50

3. A combined brush and comb, consisting of a body having a longitudinal slot, an arched cover plate on the back of the body, a comb slidably mounted in said slot to be projected beyond or to be retracted into said arched cover plate, and means to hold the comb on various lines of projection. 55

4. A combined brush and comb, consisting of a handle and a body having a longitudinal slot, an arched cover plate on the 65 back of the body, a comb slidably mounted in said slot to be projected beyond or to be retracted into said arched cover plate, said comb having a plurality of parallel cam slots formed therein, pins extending transversely in said longitudinal slot in engagement with said cam slots, means in the handle to slide the comb, and means to hold the comb in various positions of projection. 70

5. A combined brush and comb, consisting of a body having a longitudinal slot, an arched cover plate on the back of the body, a comb slidably mounted in said slot to be projected beyond or to be retracted into said arched cover plate, said comb having a plurality of parallel cam slots formed therein, pins extending transversely in said longitudinal slot in engagement with said cam slots, a rod mounted in the slot, a bridge-piece slidable on the rod and means 85 connecting the bridge-piece to the comb so that sliding movement of the former causes the latter to be projected or retracted. 80

In testimony whereof, I affix my signature in the presence of two witnesses.

CLARENCE M. DEASON.
